NAIL STRIPPER

Emil E. Werner, Lodi, Calif., assignor of one-half
to Lydia E. W. Feits, Glendale, Calif.

Application October 3, 1938, Serial No. 233,088

5 Claims. (Cl. 1—49.7)

My invention relates to nail holders and more particularly to that class known as nail strippers.

One of the principal objects of my invention is to provide a nail stripper equipped with means whereby nails are automatically fed into a readily accessible nail extracting position.

Another object of my invention is to provide a device of the above described character equipped with adjustable means for varying the feed of nails being fed to the extracting position.

A further object of my invention is to provide a device of the above described character equipped with means for accumulating nails accidentally discharged during the feeding operation whereby the same may be readily introduced into the stripper for use.

A still further object of my invention is to provide a device of the above described character which is simple in construction, automatic in operation and efficient in use.

Other objects and advantages will be apparent from the following description, appended claims and annexed drawings.

Referring to the drawings wherein like reference characters designate like parts throughout the several views:

Fig. 1 is a side elevation of my invention illustrating the same carried by a nailer.

Fig. 2 is a rear elevation of my invention on an enlarged scale.

Fig. 3 is a sectional view taken on a line 3—3 of Figure 1.

Fig. 4 is a vertical sectional view taken on the line 4—4 of Figure 3 and looking towards the front of the stripper and depicting the arrangement of the chute with respect to the hopper and subjacently arranged tray.

Fig. 5 is a detail vertical sectional view taken on the line 5—5 of Figure 1 and looking towards the rear of the stripper and depicting the rear ends of the rail members extending through the opening formed in the rear wall of the frame.

Fig. 6 is a horizontal sectional view taken on the line 6—6 of Figure 3 and looking towards the bottom of the stripper and depicting the arrangement of the track with respect to the tray and the means for adjusting the track with respect to horizontal and relative lateral adjustment of the rails of the track.

Fig. 7 is a detail vertical sectional view taken on the line 7—7 of Figure 3 and looking towards the lower end of the chute and illustrating the

manner in which the track is connected to said lower end of the chute.

Fig. 8 is a detail vertical sectional view taken on the line 8—8 of Figure 3 and illustrating the positioning of the rails of the track with respect to the adjusting means therefor.

Fig. 9 is a disassembled perspective view of the means for effecting adjustment of the track to vary the inclination thereof and to effect lateral adjustment of the rails of the track with respect to each other.

Fig. 10 is a sectional view taken on the plane of the line 10—10 of Figure 3 and illustrating the track in its uppermost adjusted position and the rail members in their maximum spaced positions with respect to each other.

Fig. 11 is a view similar to Figure 10 but illustrating the track in its lowermost adjusted position and the rail members in their minimum spaced positions with respect to each other.

In practising my invention I provide a frame 10 of a substantially U-shaped construction having a hopper 11 secured in the upper end thereof by means of rivets 12. Pivotally connected to the front end of the hopper 11, as at 13, is a chute 14 having inclined side walls 15 for receiving nails discharged from the hopper 11. The chute 14 is provided with a nail receiving track 17 (see Figure 4) on which are received nails discharged from the chute 14. The track 17 comprises a pair of parallel spaced rail members 16, the outer ends of which extend through an opening 18 formed in the frame 10.

The opposite ends of the rail members are provided with laterally offset sections 16a which terminate in upwardly extending portions 16b for effecting jointure with the chute 14. The portions 16b are spaced apart sufficiently to permit the passage of nail heads as illustrated in Figure 7 of the drawings and for a purpose hereinafter set forth. Obviously, nails discharged from the hopper into the inclined chute 14 will, due to the inclination of the walls 15, adjust themselves in such a manner that the shanks thereof will project downwardly between the walls 15 and the head sections engage said walls to effect suspending engagement with the faces of the walls.

Due to the inclination of the chute 14, the nails will gravitate onto the track 17, the shanks extending between the rail members and the head supported thereby in overlapped relation. The inclination of the rail members is such as to cause the nails to gravitate towards the frame, the frame serving to limit the gravitation there-

of. In this position, as clearly illustrated in Figures 3 and 7, the nails may be extracted for use between the portions 16b of the rail members at the jointure with the chute 14, the portions 16b being of a sufficient width to permit the passage of the nail heads therethrough as heretofore stated.

Mounted on the lower end of the frame 10 is a tray support having bottom, side and front walls 19, 20 and 21, respectively, in which is positioned a tray 22 fashioned with a downwardly extending top wall 23 formed with a longitudinally extending slot 24. The wall 21 extends upwardly in front of the tray 22 and coacts therewith to prevent accidental dislodgement of the tray from the tray support. Nails accidentally dislodged from the chute 14 will be received by the tray 22 and guided therein through the slot 24 by means of the inclined top 23. When the tray 22 becomes filled or it is desired to refill the hopper 11, the tray is elevated at the front end thereof over the wall 21, withdrawn from the tray support and the contents thereof emptied into the hopper 11. A suitable cover 25 is pivoted to the hopper, as at 26, and retains the nails therein for discharge onto the chute 14. The side walls of the chute 14 are secured in spaced relation by means of a bolt 27 secured thereto by suitable nuts.

The tray support and the lower end of the frame 10, on the rear side thereof, have secured thereto a strap 28 adapted to be secured about the waist of the operator and another strap 29 is secured to the strap 28 and extends over the shoulders of the operator for connection with the rear wall of the hopper 11, as indicated at 30, the same being clearly illustrated in Figures 1 and 2 of the drawings.

Pivottally connected to the upper end section of the hopper 11, adjacent the chute end thereof is a gate 32 adjustable relative to the open end of the hopper by engagement with an arcuate shaped rack member 33 secured to one of the side walls of the hopper whereby to govern the flow of nails from the hopper into the chute. A handle 34 is connected to the gate for permitting ready adjustment of the same.

Secured to the frame 10 is a guide member 37 having sides formed with guideways 37a and fashioned with an opening 38 registering with the opening 18 and through which the ends of the rail members 16 extend. Slidably mounted within the guideways 37a of the member 37 and frictionally engaging the sides thereof is a slide 39 fashioned with guideways 39a and with a horizontally extending slot 39b through which the ends of the rail members extend and which permits raising or lowering of the rail members upon operation of said slide 39 to adjust the inclination of the track 17. Slidably mounted within the guideways 37a and overlying the slide 39 is a plate 40 fashioned with a pair of upwardly and outwardly extending slots 40a through which the ends of the rail members 16 project. The sides of the plate frictionally engage the walls defining the guideways 39a of the slide 39. The slide 39 and plate 40 are equipped with finger-pieces 41 and 41a respectively whereby the same may be adjusted relative to each other and to the member 37.

Obviously, by moving the slide 39 and plate 40 together, the inclination of the track 17 may be varied to govern the flow of nails discharged from the chute 14, reference being had to Figures 10 and 11 wherein the track is disclosed in its

uppermost and lowermost positions respectively. By adjusting the slide 39 with respect to the plate 40, the inclined walls of the slot 40a serve to vary the space between the rail members 16 whereby nails of various sizes may be slidably accommodated therebetween, Figures 10 and 11 depicting the maximum and minimum spacing of the rail members 16 relative to each other respectively.

It is to be understood that the motions of the operator or naler during nailing operations will automatically cause the nails to be discharged from the hopper 11 onto the chute 14 in the foregoing described manner. While my device as shown and described is constructed for the use of right-handed operators, it is to be understood that the same may be constructed for left-handed operators by arranging various parts in opposite order.

While I have shown and described my invention in connection with the use of nails, it is to be distinctly understood that screws and the like may be used and that the structure may be modified to accommodate such articles without departing from the spirit of the invention or scope of the appended claims.

What I claim is:

1. A device of the character described, comprising, a frame, a hopper mounted in said frame at the upper end thereof, a chute subjacent said hopper and pivotally connected thereto and provided with a nail receiving track extending through and adjustable relative to said frame, adjustable means mounted on the frame and connected to said track and operable with respect to the frame to vary the inclination of said chute and track relative to said hopper, and a tray subjacent said track and carried by said frame for receiving nails or the like accidentally dislodged from said chute.

2. A device of the character described, comprising, a frame formed with an opening, a hopper mounted in said frame at the upper end thereof, a chute subjacent said hopper and pivotally connected to the latter and provided with nail receiving rail members extending through said opening to permit adjustment of said members with respect to said frame, adjustable means mounted on said frame and connected to said rail members and operable with respect to said frame to vary the inclination of said chute and rail members relative to said hopper, and a tray subjacent said chute and carried by said frame for receiving nails or the like accidentally dislodged from said chute.

3. A nail stripper comprising a frame, a hopper mounted in said frame, a chute subjacent said hopper and pivotally connected thereto and having a nail receiving track extending through and adjustable relative to said frame, adjustable means mounted on said frame and connected to said track and operable to vary the inclination of said chute and track relative to said hopper.

4. A nail stripper comprising a frame formed with an opening, a hopper mounted in said frame, a chute subjacent said hopper and pivotally connected thereto and provided with nail receiving rail members extending through said opening to permit adjustment of said members with respect to said frame, adjustable means mounted on the frame and connected to said rail members and operable with respect to the frame to vary the inclination of said chute relative to said hopper.

5. A nail stripper comprising a frame formed with an opening, a hopper mounted in said frame,

a chute subjacent said hopper and pivotally connected thereto, rail members connected to said chute and laterally adjustable with respect to each other and extending through said opening to permit adjustment of said members with respect to said frame, slide means mounted on said frame and connected to said rail members and

5 operable to vary the inclination of said chute with respect to said hopper, and an adjustable plate associated with said means for effecting relative lateral adjustment of said rail members upon operation of said means with respect to said frame.

EMIL E. WERNER.
